Attorney

UNITED STATES PATENT OFFICE.

ALBERT T. VAN ALSTYN, OF NEW YORK, N. Y.

CLASP FOR SANITARY BELTS.

1,172,504.

Specification of Letters Patent. Patented Feb. 22, 1916.

Application filed April 26, 1915. Serial No. 23,883.

To all whom it may concern:

Be it known that I, ALBERT T. VAN ALSTYN, a citizen of the United States, and resident of New York, in the county of 5 New York and State of New York, have invented certain new and useful Improvements in Clasps for Sanitary Belts; and I do hereby declare the following to be a full, clear, and exact description of the invention, 10 such as will enable others skilled in the art to which it appertains to make and use the same.

My invention relates to a buckle of that type having protected prong ends, and it is 15 particularly adapted for use where it is desired to have the parts which are buckled together remain in buckled relation until manually released, as in the case of straps or bandages such as sanitary napkins and 20 the like which are under strain.

It is one of the objects of my invention to provide a buckle, the prongs of which are automatically clasped, and in which the 25 ends of the prongs remain in a locked and protected position until manually released.

Still another feature of the invention is the provision of pockets to protect and lock the ends of the prongs, the prongs being 30 formed resiliently and for engagement with the pockets, when pressure is exerted thereon, to compress the prongs toward each other a predetermined amount and then release the same, thereby snapping the ends 35 into the pockets where they remain in a locked and protected position.

Still another object of my invention is the provision, in a buckle of the clasp type, of a novel spring arrangement in a multiple prong member, the resiliency being in oppositely tensioned coiled springs located at the 40 foot of the prongs.

Other novel features of my invention are discernible from the following specification, taken in connection with the accompanying 45 drawing annexed hereto, and in which:

Figure 1 is a plan view of a buckle constructed according to my invention, and showing the prongs in the unclasped position. Fig. 2 is a sectional view on the line 50 2-2 of Fig. 1. Fig. 3 is a sectional view on the line 3-3 of Fig. 1. Fig. 4 is a perspective view showing a modified form of pocket

for receiving and protecting the ends of the prongs. Fig. 5 is a perspective view showing the manner in which the pocket shown 55 in Fig. 4 is formed. Fig. 6 is a plan view showing pockets struck out of the frame. Fig. 7 is a sectional view on the line 7-7 of Fig. 6. Figs. 8 and 9 illustrate another modified form of pocket and the manner of 60 forming the same. Fig. 10 shows the double pronged resilient pin bar.

Referring in detail to the drawings, which illustrate buckles embodying the principles of my invention, and with particular reference to Figs. 1 to 3 inclusive and Fig. 10, the frame 1 of the buckle clasp is preferably 65 formed of sheet material and comprises a stirrup portion 2 which provides means for attaching a looped strap, and a throat portion 3, said last-named portion being separated from the stirrup portion by a transverse bar 4, rolled at 5 to provide a hinge mounting for the pronged member 6 illustrated in Fig. 10. The pronged member 6 70 comprises a pintle portion 7 having at each end thereof oppositely coiled springs 8, and from these springs extend the parallel prongs 9 which are substantially at right angles to the pintle portion 7. The springs 80 8 are so tensioned that the prongs resist pressure tending to force them toward each other. In mounting the pronged member 6 upon the frame of the buckle, the pintle portion 7 is disposed loosely within the roll 85 5, thereby forming a hinge. The prongs 9 are preferably shaped to pin points at 10 so as to easily penetrate the material to which the buckle is applied.

Opposite the transverse bar 4, and in 90 proper position to receive the pin points 10, are formed pockets 11 for the reception of the pin points. These pockets are formed as shown in Fig. 3 by bending portions of the material forming the frame upwardly 95 and inwardly to form opposite pockets having adjacent inclined faces as at 12, this feature being shown best in Fig. 3.

As stated, the pockets 11 are formed opposite each other and the adjacent faces 12 are 100 inclined for engagement by the prongs 9. In clasping the prongs, they are pressed downwardly toward the frame member, thus causing them to engage the inclined

faces 12 of the pockets which press the prongs 9 toward each other thereby compressing the springs 8 until the pin points 10 pass the lower edges 13 of the inclined faces 12. As soon as they pass the edges 13 the springs 8 snap the prongs 9 into their normal position and the pin points 10 pass underneath the lower edges 13 of the inclined faces 12 and into the pockets 11 where they remain in the locked and protected position shown in Fig. 3 until manually released.

In applying the buckle, (referring to Fig. 1), a looped strap 14 is passed through the stirrup 2 and fastened. The free strap 15 is then passed underneath the throat 3 and upwardly therethrough. The prongs 9 are then pushed through the material of the strap 15 and the strap 15 is pulled in the direction indicated by the arrow in Fig. 1, this draws the prongs 9 down against the inclined faces 12 and forces the pin points 10 toward each other by reason of their engagement with the said inclined faces 12, and as soon as they pass under the edges 13 of the faces 12 they snap into the locked and protected position as hereinbefore described.

To release the points it is only necessary to press the two prongs toward each other which serves to dislodge the points 10 from the pockets 11 and the prongs may then be raised to release the material. It is to be noticed, that due to the formation of the pockets with inclined adjacent faces, any strain in the direction of the arrow tending to pull the strap from the buckle will only serve to automatically lock the prongs.

There are other forms of pockets which will cause the same action and some of these forms I have illustrated in Figs. 4 to 9 inclusive.

Referring particularly to Figs. 4 and 5 in which I have illustrated a closed form of pocket. This pocket is blanked out of the material forming the frame in the manner shown in Fig. 5, that is, by forming the L-shaped tab 16, the longer leg of which is turned up at right angles to the member 3 as shown in Fig. 5. The upper portion of this is then turned over at right angles to itself on the line 17 and the shorter leg 18 of the L-shaped tab is then turned downwardly on the line 19 thus closing the pocket on the outside. The inner corner 20 is then bent downward toward the member 3 to form an incline for engagement with the pronged member as set forth in the description in connection with Figs. 1 to 3 inclusive.

In Figs. 6 and 7 I have shown the pockets or guards struck up from the material forming the frame, the adjacent faces being inclined in the same manner as are those in the form shown in Figs. 1 to 3.

In the pocket shown in Figs. 8 and 9, a

fin 21 is formed when the frame member 1 is blanked out. This fin is bent upwardly and over as shown in Fig. 9, and the edge 22 thereof is inclined for engagement with the pronged member 6.

While I have herein shown and described specific forms of my invention, it is to be understood that I do not limit myself to the forms shown and described except in so far as the scope of my claims import.

It is also to be understood that while I have herein shown a pronged member having pin points, I do not limit myself to prongs having points but, as for instance where a strap is used which is provided with eyelet holes, I may use a pronged member having blunt ends.

I claim:

1. In a buckle including a frame comprising stirrup and throat portions, a bar separating said portions, a multiple pronged spring member pivotally mounted on said bar, pockets on said frame opposite said bar for the reception of the ends of said prongs, said pockets having adjacent sides oppositely inclined for engagement with said prongs to compress the latter upon pressure being exerted thereon and allow the same to finally spring into a protected and locked position in said pockets.

2. In a buckle including a frame comprising stirrup and throat portions, a bar separating said portions, a double pronged member pivoted to said bar and each prong provided with a coil spring said springs being oppositely tensioned with respect to each other, pockets on said frame opposite said bar for the reception of the ends of said prongs, said pockets having the adjacent sides oppositely inclined for engagement with said prongs to compress said springs upon pressure being exerted on said prongs and allow the latter to finally spring into a protected and locked position in said pockets.

3. In a buckle including a frame, a multiple pronged spring member mounted in said frame, and point pockets having inclined upper sides for engagement with said prongs to compress the latter and cause the same to finally spring into a protected and locked position in said pockets.

4. In a buckle including a frame, a multiple pronged spring member mounted in said frame and for penetrating the body to be buckled, and point pockets having the adjacent upper sides oppositely inclined for engagement with said prongs when the body to be buckled is pulled in a direction coincident with the direction of said prongs whereby the latter are compressed and finally sprung into a protected and locked position in said pockets.

5. The combination in a buckle including a resilient multiple pronged member, of

pockets to receive and retain the pointed ends of the prongs of said member, said pockets being provided with inclined sides for engagement with said pointed ends to compress said prongs and cause the ends thereof to finally spring into a protected and locked position.

In testimony whereof, I have signed this specification in the presence of two subscribing witnesses.

ALBERT T. VAN ALSTYN.
